UNITED STATES PATENT OFFICE.

HARRY K. HEDGES, OF LOS ANGELES, CALIFORNIA.

PUMP.

1,262,665.

Specification of Letters Patent. Patented Apr. 16, 1918.

Application filed October 28, 1914. Serial No. 868,978.

To all whom it may concern:

Be it known that I, HARRY K. HEDGES, a citizen of the United States, residing at Los Angeles, in the county of Los Angeles and 5 State of California, have invented new and useful Improvements in Pumps, of which the following is a specification.

This invention relates to pumps, and more particularly to that class of pumps designated 10 as displacement pumps, in which compressed air is utilized for raising liquids, by application of the compressed air directly on the surface of successive charges of the liquid, such charges being thereby driven 15 out of suitable displacement chambers.

The invention has for its object to provide a pump of the general character stated, which will be relatively simple and inexpensive in construction, positive, highly efficient 20 and economical in operation, and which will be generally superior in reliability and serviceability.

The invention contemplates the use of a plurality of submerged displacement chambers 25 having a common distributer for the compressed air supply, the organization of the pump being such that the distributer may be placed at a distance from the submerged chambers, as for instance at the 30 mouth of the well or any other suitable point, and connected to said chambers by means of a pipe leading to each such chamber. Control of the inlet and discharge of fluid to and from such chambers is thus 35 effected by the distributer through the medium of the elastic working fluid itself, the pipe of each chamber serving alternately as a supply and discharge pipe for the elastic medium used in its respective chamber.

With the above and other objects in view, the invention consists in the novel and useful provision, formation, combination, association and relative arrangement of parts, members and features, and the general organization and mode of application and operation thereof, all as hereinafter described, shown in the drawing, and finally pointed out in claim.

In the drawing:

Figure 1 is a fragmentary vertical transverse sectional view of a portion of a deep well, such as a deep oil well, showing the improved pump installed therein, the displacement chambers being shown as submerged 55 in the liquid to be pumped;

Fig. 2 is a horizontal transverse sectional

view taken on the line x^2-x^2 , Fig. 1, and looking in the direction of the appended arrows, the showing of the liquid being omitted from this figure for clearness of illustration;

Fig. 3 is a view similar to Fig. 2, taken on the line x^3-x^3 , Fig. 1, and looking in the direction of the appended arrows; and

Fig. 4 is a transverse sectional view 65 through the distributer, taken on the line x^4 , Fig. 1, and looking in the direction of the appended arrow.

Corresponding parts in all the figures are designated by the same reference characters. 70

Referring with particularity to the drawing and the embodiment of the invention therein illustrated, A designates generally the hole of a deep well within which liquid to be pumped is shown at a. The improved 75 pump is shown as comprising in the main a plurality of displacement chambers B and C and a distributing timer D, the distributing timer D communicating by means of pipes b and c with the displacement chambers B and C, respectively.

The displacement chambers B and C are preferably formed in a common cylindrical shell 5, a vertical transverse partition 6 dividing such shell 5 to form the chambers. 85 In the partition 6 is formed a discharge duct 7 which begins at the top end wall 8 which closes the cylindrical shell 5 and terminates at a point slightly above the bottom end wall 9, which closes the cylindrical shell 5, as at 90 10. At the terminus 10 of the duct 7 is provided a horizontal valve runway 11 establishing communication between the duct 7 and the chamber B through a port 12 and establishing communication between the duct 7 and the chamber C through a similar port 13, a ball valve 15, free to travel in the runway, serving to cover and uncover the ports 12 and 13 alternately as the intake of liquid to, or discharge of liquid from the chambers 95 B and C is alternately performed. A plurality of bars 16 constituting a track are provided at the point of junction of the duct 7 and valve runway 11 to confine the ball valve 15 to the runway as it traverses the 100 runway to alternately close the ports 12 and 13. A discharge pipe 17 is threaded into the top end wall 8 of the cylindrical shell 5 as at 17a. This discharge pipe communicates with and forms an extension of the duct 7. The 110 chambers B and C are each provided with a ball check valve 18 and 19, respectively.

Seats 18^a and 19^a is formed in plugs 18^b and 19^b respectively, such plugs being threaded into the bottom wall 9 of the cylindrical shell 5. Valve cages 18^c and 19^c are 5 formed on the plugs 18^b and 19^b, respectively, to confine the valves 18 and 19 to the proper path of travel toward and away from their respective seats. The valves and seats may be removed for cleaning or repairing 10 when required, by removal of the plugs 18^b and 19^b.

The distributing timer D comprises a casing 20 and a rotatable plug 21 in said casing, said plug being provided with 15 means *d* whereby the same may be rotated in the casing. The casing is provided at the top with inlet ports 20^a and 20^b and exhaust ports 20^c and 20^d, and at a point diametrically opposite said inlet and exhaust ports 20 the casing is further provided with ports 21^a and 22 which communicate with the pipes *b* and *c* respectively. The preferred form of rotatable plug is provided with 25 pockets 23 and 23^a at diametrically opposite points, said pockets being adapted to register alternately with the intake port 20^a in the casing. Further pockets 24 and 24^a are provided in the rotatable plug at diametrically opposite points and are adapted 30 to be brought alternately into registration with the pipe *b*. A duct or bore 25 connects the pocket 23^a and the pocket 24^a and a similar duct or bore 26 connects the pocket 23 and the pocket 24. A diametrical bore 35 27 extends through the plug at an angle of approximately 90° from the bores 25 and 26, said duct or bore 27 terminating at each end in a pocket 28. The ports 20^a, 20^c and 21^a with the pockets 23, 23^a, 24, 24^a and 28 40 with their respective connecting ducts all pertain to the control of the elastic working medium in its admission to and exhaust from the chamber B. The rotating plug is further provided with pockets 29 at diametrically opposite points, these pockets being adapted to communicate with the inlet port 20^b of the casing. Further diametrically opposed pockets 30 are connected by 45 ducts 31 and 32 each to that pocket 29 which is disposed on the opposite side of the rotatable plug from the respective pockets 30. Further diametrically opposed pockets 33 and 33^a are provided in the rotatable plug and adapted to register with 50 the exhaust port 20^d and the port 22, these pockets 33 and 33^a being connected by a diametrically extending duct or passage 34. The ports 20^b, 20^d and 22 in the casing and the pockets 29, 30, 33 and 33^a with their 55 respective ducts are features entering into the control of the admission and exhaust of the elastic working medium to the chamber C through the pipe *c*. Connection is made with a suitable source of compressed air 60 through the pipes 35 and 36 which termi-

nate in the ports 20^a and 20^b of the casing 20. Exhaust pipes 37 and 38 communicate with the ports 20^c and 20^d. The means for rotating the plug 21 may comprise a pulley 39 or any other suitable means for connecting with a power supply. To take up the wear the rotatable plug is preferably conical, its seat in the casing 20 being complementarily formed. The plug is provided with a stem or shaft 40 to which the rotating means *d* is secured, adjusting devices 41 for the conical plug 21 being also provided on the shaft 40. 75

The operation, method of use and advantages of the improved pump will be readily 80 understood from the foregoing description, taken in connection with the accompanying drawing and following statement:

The pump being submerged liquid will 85 rise in that chamber in which the pressure is relieved or which is connected through its pipe *b* or *c* with its respective exhaust pipe through the distributing timer, the liquid in entering unseating the respective valve 18 or 19. The timer then being given 90 a quarter turn communication of the chamber with its exhaust port is terminated and the chamber then communicates with its respective air supply pipe. Compressed air being then admitted, the liquid is expelled 95 from such chamber through the duct 7, the valve 18 or 19 having seated as soon as ingress of the liquid to the chamber ceases, the valve 15 being forced to that seat opposite the chamber being discharged. While 100 one chamber is thus discharging the other chamber is being allowed to communicate with its exhaust pipe through the distributor. As the control pockets and ducts for each chamber are spaced approximately 90° 105 apart on the rotor, it will thus be seen that each chamber alternately receives a charge of compressed air and is alternately connected through the distributor with its respective discharge pipe. The valve 15 is 110 thus caused to rest against its seat 12 when the chamber C is discharging and the seat 13 when the chamber B is discharging. The planes of the valve seats 12 and 13 are 115 preferably at an angle to the vertical, this arrangement assisting in keeping the seats free from sand or other foreign matter.

Having thus described my invention, I claim and desire to secure by Letters Patent:

In apparatus of the character disclosed, means for controlling the distribution of a pressure medium to displacement chambers of a pump and the exhaust of the pressure medium from said chambers, comprising a 125 casing having a plurality of inlet and exhaust ports therein and having other ports for communication with displacement chambers, a valve body rotatable in said casing and having passages therein for registration 130

with the last named ports and said inlet ports; and other passages for registration with said last named ports and said exhaust ports, said passages connecting said inlet ports with said last named ports and connecting said exhaust ports with said last named ports and being adapted for alternate registration with said intake and exhaust ports, means for operating said valve body so that the last named passages are alternately brought into registration with the last named ports, said last named passages

having their inlet ends connecting said inlet ports and said last named ports, and being in a plane other than that in which said 15 exhaust ports lie.

In testimony whereof, I have signed my name to this specification in the presence of two subscribing witnesses.

HARRY K. HEDGES.
